UNITED STATES PATENT OFFICE.

HALBERT K. HITCHCOCK, OF PITTSBURGH, PENNSYLVANIA, ASSIGNOR TO PITTSBURGH PLATE GLASS COMPANY, A CORPORATION OF PENNSYLVANIA.

APPARATUS FOR POLISHING PLATE GLASS.

Application filed October 29, 1923. Serial No. 671,374.

The invention relates to an apparatus for polishing plate glass. It is particularly adapted for use in a straight away operation in which the glass to be surfaced is passed continuously beneath a series of grinding and polishing machines, and the invention has its greatest value in this connection, but it is not limited to use in such connection. It has for its primary objects the provision of an improved apparatus, wherein, (1) a uniform polishing effect is secured over the area of glass passing beneath the apparatus, (2) the polishing mixture is distributed uniformly over the faces of the polishing felts, (3) the faces of the felts are automatically cleaned at intervals which can be regulated to suit conditions, (4) the amount of polishing mixture to each felt can be independently regulated so as to be suitable for each character of work being done, (5) the conduits for the polishing mixture are kept open and all danger of clogging avoided, and (6) any waste of the polishing mixture is avoided and all splashing of the polishing mixture eliminated.

Certain embodiments of the invention are illustrated in the accompanying drawings wherein:

Figure 1 is a vertical section through one form of apparatus. Fig. 2 is a plan view of the apparatus of Fig. 1. Fig. 3 is a section on the line III—III of Fig. 1. Fig. 4 is a vertical section through a modified form of the apparatus. Fig. 5 is a plan view of the apparatus of Fig. 4. And Fig. 6 is a diagrammatic side elevation view partially in section showing the method of circulating and mixing the rouge and water.

Referring to the construction of Figs. 1, 2 and 3, 1 is the spindle housing in which is mounted the spindle 2 which projects from the lower end of the housing and is secured to the runner frame 3 by means of the key 4. The runner frame is preferably a steel casting of the skeleton form indicated in Fig. 2 and carries five runner blocks 5, although this number may be varied to suit requirements, it being preferred, however, to use runner blocks of relatively large diameter as compared with those ordinarily used so that a less number are used than if smaller runner blocks were employed.

The runner blocks are of annular form, as indicated in Fig. 1 and carry upon their lower sides the annular discs 6 of felt or other yielding material suitable for use with rouge or

other polishing material, such felts being preferably secured to the runner blocks by means of water proof cement. The runner blocks are provided with hollow shafts 7 which are secured to such blocks by means of rubber diaphragms 8 clamped at their inner edges to the flanges of the shafts by means of the collars 9 held in place by screws or bolts and at their outer edges by means of the collars 10 held in place by the bolts 11. The shafts are journaled in the bearings 12, provided with suitable bushings, and disengagement of the shafts from the bearings, when the runner frame is raised, is prevented by means of the caps 13 which are screwed down into the ends of the shafts as indicated at 14. The perforations 15 through the centers of the shafts provide conduits for the passage of a polishing mixture to the spaces at the centers of the blocks, and the diaphragms 8 prevent any splashing or loss of the polishing mixture.

Mounted upon the top of the runner frame is a casting 16 provided with the five annular troughs 17, 18, 19, 20 and 21 which communicate with the passages 15 through the runner block shafts by means of the pipes 22, 23, 24, 25 and 26. These annular troughs are supplied from the container 27 by means of the pipes 28, 29, 30, 31 and 32.

Secured in fixed position in the container 27 is a transverse box 33 divided up into five compartments 34, 35, 36, 37 and 38, each of which communicates with one of the pipes as indicated in Fig. 3 which shows the connection of the compartment 36 with the pipe 30. The compartments are supplied intermittently with the rouge mixture in the container 27 by means of the wheel 39 mounted for rotation and provided with the five buckets 40, 41, 42, 43 and 44 mounted to swing freely on the rods 45 extending between the sides of the wheel, these buckets being arranged in different vertical planes, so that each one supplies one of the compartments 34, 35, 36, 37 and 38. The swinging movement of the buckets in one direction is stopped by means of the stop members 46 on the periphery of the wheel, so that upon the rotation of the wheel in the direction indicated by the arrow in Fig. 1, each bucket scoops up a quantity of the polishing mixture, and when it arrives at the position of the bucket 42 in Fig. 1, the contents is dumped into a compartment in the box 33.

1, each bucket scoops up a quantity of the polishing mixture, and when it arrives at the position of the bucket 42 in Fig. 1, the contents is dumped into a compartment in the box 33.

The container 27 is supplied with a mixture of rouge and water or other polishing material through the spigot 47, and a water pipe 48 is also provided to give an independent supply of water, such pipe being controlled by means of the valve 49. The method of supplying the mixture to the pipe 47 is illustrated diagrammatically in Fig. 6 in which 50 is a mixing tank or laxivator provided with a circulation main 51 leading from the bottom and having its other end leading back into the top of the tank as indicated at 52. A circulation of the mixture is secured by means of a pump 53. Proper proportions of rouge and water are supplied to the tank and the mixture is kept agitated and thoroughly mixed by means of paddles 54 carried by the shaft 55, such shaft being driven by the belt 56 passing around a pulley 57 on the upper end of the shaft, or by any other suitable means. Leading from the main 51 are the spigots 47 which go to the various polishing machines. This method of circulation and mixing insures that the water and rouge will be thoroughly mixed and that the mixture furnished to all of the polishing machines through the spigots 47 will be the same. The main 51 is preferably made of wood as are also the spigots 47 in order to resist the action of the rouge composition, which is acid in character, although corrosion resisting metal might be used. The main is preferably carried along over the various machines so that the spigots can discharge directly into the containers 27. There is thus little danger of the mixture clogging in its passage from the main to the container, and if this occurs, the difficulty may quickly be removed by removing the spigot and inserting a new one. The wheel 39 is driven from the counter shaft 58 by means of the belt 59 (Fig. 3), the step pulleys 60 and 61 being employed so that the speed of rotation of the wheel may be regulated to give any desired interval of feed. The amount of feed may be varied by varying the level of the liquid in the container 27.

As indicated in Fig. 2, the glass sheet 62 which is being polished is carried upon a table or car 63, and the width of the glass is such that all of the felts on the runner blocks will eventually overhang the edge of the glass when the runners are in their side positions. This arrangement of overhang provides a means for cleaning the blocks which, in a continuous operation such as this, would otherwise cake up with rouge and with the infinitely fine particles of glass removed in the polishing operation and become ineffective in the course of time. By means of the feed arrangement as heretofore described, a mixture of rouge and water of the proper character is supplied to each runner at separated intervals, in sufficient quantity so that when a discharge of the mixture occurs to a runner block, its surface is so softened that the rouge forms

a new face free from the defects before noted, the old surface being scraped off more or less as the runner passes over the edges of the glass sheet depending somewhat on the amount of liquid used. The interval of feed is so arranged that this surfacing effect is secured only when the blocks become ineffective so that the rouge is not scraped off before it has had an opportunity to do the amount of polishing work which it should do. When it is necessary to give the felts a more thorough cleaning than is afforded by this regular intermittent discharge of rouge and water, it may be accomplished by increasing the volume of the mixture in the container 27 by adding water so that it is very thin, or by using only water in the container for a short time or feeding water directly to the blocks from a hose.

The discharge of the rouge mixture to the centers of the runners is advantageous, since there is no waste and the rouge is immediately spread between the felt and the glass. The annular felt thus acts somewhat as a brush distributing the rouge mixture over the surface of the glass so that the face on the felt is quickly reformed and there is a minimum amount of waste incident to the mixture flowing off of the side of the table. This feature and the supplying of the rouge beneath the diaphragms 8 promotes economy in the use of polishing material and assists in preventing an accumulation of rouge over the surface of the runner frame and blocks and protecting the bearings and other parts from the corroding action of the rouge mixture. In this connection, the hollow shafts 7 are preferably made of some acid resisting composition so that they will last for a long period despite the corroding action of the rouge mixture.

A further substantial advantage is also involved in arranging the rouge discharge streams so that their outlets follow the pads in their paths of movement in that the mixture of rouge and water gives a cooling effect upon the glass where it is of the greatest value. The tendency of the annular series of pads or blocks is to heat the glass in an annular ring which may cause breakage due to unequal expansion after the glass has passed beneath a number of runners; and the supply of rouge following along the annular paths tends to compensate for this condition.

The method of feed, including the arrangement illustrated in Fig. 6 is also of advantage since it permits all of the machines of a series to be fed from the same container or tank 50. The various machines of a series require a mixture containing a less and less proportion of rouge as the polishing progresses, and this condition may be readily secured in the apparatus as above described by supplying a rouge mixture of the same character to all of the containers 27 by means of the spigots 47 and then utilizing the water

pipes 48 to dilute the mixture to the proper consistency for the particular polishing stage for which the machine is being used. If desired, the excess of water to give the necessary dilution may be applied to the stream of rouge mixture anywhere along its travel to the table, or may be supplied to the table, itself, the result being the same in all cases.

10 Figs. 4 and 5 illustrate a modification, such modification relating to the runner block construction and the method of supplying the rouge mixture from the annular troughs to the blocks, the other parts of the apparatus being the same as described in connection with the apparatus of Figs. 1 to 3, and being similarly numbered. In this type of construction the runner block 64 is provided with an annular clamp 65 held by the bolts 66, and between this clamp and the block is secured a rubber diaphragm 67 corresponding to the diaphragms 8 of Fig. 1, but provided with perforations 68, the inner edge of the diaphragm being clamped to the sleeve 69 by means of the bolts 70. The upper end of the sleeve 69 is threaded to a cap 71 and this cap is secured against the lower side of the runner frame 72 by means of the bolt 73 which has a collar or shoulder 74 fitting between the top of the sleeve 69 and the flange on the cap 71. The lower portion of the bolt 73 acts as a spindle or pivot, the sleeve 69 serving as the bearing therefor. The clamp 65 is provided, with a splash wall 75 and the space inside of this wall is fed with a rouge mixture from the pipe 76 leading from one of the annular troughs or grooves 77, such troughs or grooves being fed by means of the pipes 78 corresponding to the pipes 28 to 32 of the Fig. 1 construction. In this construction as in that of Fig. 1, the diaphragm which connects the runner block to the spindle is relatively flexible so that the runner block can adjust itself to the surface of the glass. Also in this construction as in that of Fig. 1, the lower ends of the pipes leading to the annular troughs are supported by means of a bracket 79 clamped around the lower end of the spindle housing.

50 What I claim is:

1. In combination in polishing apparatus, a runner frame, having on its upper side a plurality of concentric annular troughs, a plurality of runner blocks carried by the

frame, annular polishing discs of yielding material carried by the blocks, a conduit extending down to each of said troughs for supplying a polishing mixture thereto, and conduits leading from the troughs to the openings at the centers of the discs.

2. In combination in polishing apparatus, a runner frame, a plurality of runner blocks carried thereby, a plurality of conduits for conducting a polishing mixture to the runner blocks, a container for the polishing mixture, and a rotating device in said container provided with a plurality of buckets, one for each conduit, arranged so that on the rotation of the device each bucket dips up a quantity of the mixture and discharges it into its conduit.

3. In combination in polishing apparatus, a runner frame having on its upper side a plurality of concentric annular troughs, a plurality of runner blocks carried by the frame and each provided with a facing of yielding material, a conduit extending down to each of said troughs for supplying a polishing mixture thereto, and conduits leading from said troughs to a position of discharge adjacent the runner blocks.

4. In combination in polishing apparatus, a runner frame having on its upper side a plurality of concentric annular troughs, a plurality of runner blocks carried by the frame and each provided with a facing of yielding material, a conduit extending down to each of said troughs for supplying a polishing mixture thereto, means for supplying a polishing mixture to said conduits one after the other at timed intervals, and conduits leading from said troughs to a position of discharge adjacent the runner blocks.

5. In combination in polishing apparatus, a runner frame, a plurality of runner blocks carried thereby, a plurality of conduits for conducting a polishing mixture to the runner blocks, a container for the polishing mixture, and a rotating device in said container provided with a plurality of buckets; one for each conduit, arranged in series around said rotating device so that on the rotation of the device, the buckets one after the other dip up a portion of the mixture and discharge it to one of said conduits.

In testimony whereof, I have hereunto subscribed my name this 25th day of Oct. 1923.

HALBERT K. HITCHCOCK.
